UNITED STATES PATENT OFFICE.

WALTER H. KNIGHT, OF NEW YORK, N. Y.

ELECTRIC-MOTOR REGULATOR.

SPECIFICATION forming part of Letters Patent No. 428,169, dated May 20, 1890.

Original application filed March 13, 1886, Serial No. 195,133. Divided and this application filed June 5, 1889, Serial No. 313,229.
(No model.)

To all whom it may concern:

Be it known that I, WALTER H. KNIGHT, a citizen of the United States, residing at New York, in the county of New York, State of New York, have invented certain new and useful Improvements in Electric-Motor Regulators, of which the following is a specification.

My invention, which is a division of my application, Serial No. 195,133, filed March 13, 1886, relates to controlling devices for electric motors.

It is especially adapted for motors working on a circuit of constant potential, such as is employed for electric railways. In motors of a circuit of this character it is essential that a resistance or other device for opposing the electro-motive force should be inserted in the circuit whenever the motor is at rest or its counter electro-motive force substantially diminished. Since a reversal of the motor, of course, reverses its counter electro-motive force, it is essential that it should only be reversed when the motor is at rest, and when there is substantially no current passing through it. A sudden reversal of the motor when in operation so affects the counter electro-motive force that unless a resistance is inserted the sudden flow of current which ensues is so great as to burn out the machine. Moreover, when the reversing device is a switch controlling the direction of current in either the field magnet or armature, it is apt to be injured by operating it while the current is passing.

My invention consists in providing a reversing mechanism for the motor with a stop or lock, so that it can be operated only when there is a sufficient amount of resistance inserted to prevent injury, and it, furthermore, consists in providing a stop or lock for the resistance controller or regulator of the machine, by which, when the reversing mechanism is at the neutral point, the resistance cannot be cut out. These devices absolutely prevent reversal of the motor at an improper time, and also the operation of the regulator unless the reversing mechanism is set in one direction or the other.

My invention is illustrated in the accompanying drawings, wherein—

Figure 1 is a diagrammatical view of a reversing mechanism and a regulating mechanism for an electric motor so connected as to embody my invention. Figs. 2 and 3 show the alternative condition to that shown in Fig. 1, wherein the reversing mechanism is set in opposite directions respectively.

In the drawings, A represents a reversing device for an electric motor, which in this case is shown as a lever for shifting the position of the brushes upon the commutator. The same result, however, may be accomplished by any other of the well-known means for that purpose. B is a regulator for the motor, consisting in this case of a lever controlling the resistance, cutting out more or less of it at the will of the operator.

Any other controlling device by which a variation between the direct and counter electro-motive forces is prevented from causing an injurious flow of current to the motor may be employed.

C is the resistance-lever, provided with a grooved segment D.

E is a connecting-rod from the lever A, leading to a pivoted triangular block F, provided with pins G, which pins in Fig. 1 extend into a break in the lower flange of segment D and prevent any movement of lever C. In this condition the lever A is holding the commutator-brush at a neutral point, so that no lead is given to the motor and the resistance-lever cannot be turned to throw out the resistance and admit current to the motor when it is not in a condition to generate its counter electro-motive force. When, however, the lever A is turned to one side or the other to give a direction to the motor, the block F is thrown into one or the other of the positions shown in Figs. 2 and 3. The pins G are then thrown out of the path of the flange of D, so that it may readily pass between them in either direction, whether the position taken be that of Fig. 2 or Fig. 3. The resistance can then be cut out and the motor operated and regulated at will; but when any of the resistance is cut out by a movement of lever C in either direction from the position of Fig. 1 the flange of D comes in between the two pins G and prevents any movement of block F, thereby locking the lever A in position. By

this arrangement the lever A cannot be turned to reverse the motor until the lever C is brought back to the position of Fig. 1 with the maximum resistance in circuit.

5 By the device above described it will be seen that the motor is at all times safe from accident at the hands of reckless and inexperienced operators.

What I claim as new, and desire to secure 10 by Letters Patent, is—

1. The combination, with an electric motor, of a reversing device and regulator therefor, means for operating the same, and a stop for the reversing device, controlled by the regulator, whereby the reversing device can be 15 operated only when the regulator is in a predetermined position.

2. The combination, with an electric motor, of a reversing device therefor, a regulator, 20 a stop for the reversing device, controlled by the regulator and locking the reversing device, so as to prevent its being operated except when the regulator is substantially at the point of maximum control.

25 3. The combination, with an electric motor,

of a regulator therefor, a stop or lock for the regulator, and a reversing device for the motor connected to said stop, whereby the said stop is operated by the reversing device to lock the regulator against movement, except 30 when the reversing device is in a predetermined position.

4. The combination, with an electric motor on a constant-potential circuit, of a regulator and reversing device therefor, operated independently of one another, and an intermediate stop or lock connection, whereby the regulator and reversing device each controls the movement of the other.

5. The combination, with an electric motor 40 on a constant-potential circuit, of a reversing-lever therefor, a regulating-lever, a flanged segment on the regulator-lever, a pivoted block having stops engaging with the flange of the segment, and a connection therefrom to the 45 reversing-lever, substantially as described.

WALTER H. KNIGHT.
